Des. 196,874
Patented Nov. 12, 1963

196,874

DISPENSER FOR TABLET OR SIMILAR ARTICLE

Larry L. Fites, Kalamazoo, Mich., assignor to The Upjohn Company, Kalamazoo, Mich., a corporation of Delaware

Filed Apr. 25, 1962, Ser. No. 69,849

Term of patent 14 years

(Cl. D52—3)

FIGURE 2

FIGURE 1 is a front perspective view of the dispenser for tablet or similar article embodying my new design.

FIG. 3 is an elevational view taken from the right side thereof with the container portion omitted for convenience of illustration.

I claim:

The ornamental design for a dispenser for tablet or similar article, as shown.
